UNITED STATES PATENT OFFICE.

WILLIAM R. QUINAN, OF SAN FRANCISCO, CALIFORNIA.

BLASTING-POWDER.

SPECIFICATION forming part of Letters Patent No. 252,250, dated January 10, 1882.

Application filed April 9, 1881. (No specimens.)

To all whom it may concern:

Be it known that I, WILLIAM R. QUINAN, lieutenant in the United States Army, and a citizen of the United States, residing at the city of San Francisco, in the county of San Francisco and the State of California, have invented a new and useful High Explosive, of which the following is a specification.

My invention relates to the improvement of nitro-glycerine powders in regard to strength and safety and comparative freedom from noxious gases when exploded, my object being to produce a powder which possesses great power and is at the same time very safe to handle, transport, and use, and can be exploded in confined places with less inconvenience to the miner. When blasting-powders are made by the admixture of nitro-glycerine with inert absorbents—such as kieselguhr—safety is attained at a great sacrifice of power. If an excess of nitro-glycerine is used with a view to greater strength, the powder itself becomes sensitive to blows and is liable to accidental explosion from the leakage of nitro-glycerine; and when blasting-powders are made by the admixture of nitro-glycerine with the ordinary oxidizing absorbents, though loss of power is partly obviated, there remain in such powders in varying degrees the same sensitiveness and liability to leakage. The absorbent which I use is a nitro-cellulose made from wood pulp, sawdust, or other vegetable fiber by the action of sulpho-nitric acid. If the acids used are of commercial strength, the fiber should be subjected to their action for a few minutes only. If they are diluted, the time should be increased in proportion to their dilution. Neither acid should contain more than two equivalents of water. The product is a low form of nitro-cellulose, varying in my experiments from one-half to two-thirds the explosive strength of gun-cotton or trinitro-cellulose, measured by the pressure-gage. As I use it made from wood pulp it is a fine yellow substance very much resembling (except in color) the original wood pulp. The color I do not regard as an essential characteristic. If the acids used were free from impurities, the nitro cellulose would probably be uncolored. It is capable of absorbing a very large percentage of nitro-glycerine without leaking. The higher form, or the

trinitro-cellulose made from wood pulp, is also a fair absorbent, and can be used in making the powder; but the lower form is preferable, as its holding power is superior.

55

To get a powder of great strength I mix about fifteen parts, by weight, of nitro-cellulose with about twelve parts, by weight, of pulverized chlorate or nitrate of potash, or its equivalent, and mix this with about thirty-two parts of nitro-glycerine. Thorough incorporation of these materials produces the powder, which is yellow in color and dryish, holding the nitro-glycerine in such thorough absorption that a heat of 120° Fahrenheit will not cause leakage. When first made this powder is quite safe against blows. After standing a short time it becomes still more so, partly from the more thorough absorption of nitro-glycerine, but chiefly from the natural absorption of a small percentage of moisture from the atmosphere. The same effect may be arrived at directly in the manufacture by adding three per cent. of water to the other materials. More water may be added, producing greater insensitiveness; but if too much is mixed in, a stronger primer than the ordinary triple-force cap will be required to develop the full strength of the powder.

75

The action of the moisture or water is thus explained: When an explosive is struck between two hard surfaces the sudden conversion of mechanical energy into heat will cause explosion if the temperature of the explosive is sufficiently raised. The great specific heat of water prevents this dangerous elevation of temperature, as the water absorbs and renders latent the heat of percussion. Thus the moisture or water present in this powder after manufacture is a valuable agent in producing safety against blows.

80

The powders made from chlorate and nitrate are very much alike in regard to safety against percussion. The chlorate-powder is somewhat stronger, but when in the loose state and dry it can be exploded by fire, whereas the nitrate-powder is free from this danger. Both powders, when compressed into cartridges, are safe against fire. They burn somewhat like compressed gun-cotton, but more quietly.

95

I do not confine myself to the exact proportions given above. A larger proportion of ni-

100

- tro-glycerine can be safely held by the absorbent. The strength of the powder, however, is more directly dependent upon the relative proportions of the oxidizing agent and the nitro-cellulose than upon the quantity of nitro-glycerine present. If a smaller quantity of nitro-glycerine be used, the relative proportion of chlorate or nitrate to the nitro-cellulose should be lessened, the extremes being about twelve parts chlorate or nitrate to fifteen parts nitro-cellulose when fifty-five or more parts nitro-glycerine are employed, and seven parts chlorate or nitrate to fifteen nitro-cellulose when the proportion of nitro-glycerine is less than ten per cent. When the higher form of nitro-cellulose is used the proportion of nitrate or chlorate should preferably be lessened to about ten instead of twelve parts.
- I am aware that Nobel's blasting-gelatine is made by mixing nitrated cellulose with nitro-glycerine and an oxidizing ingredient; but other and inert ingredients are added which reduce the explosive force of the compound and produce highly deleterious gases on explosion, and the proportion of nitrated cellulose is very small and undergoes by gentle heating a kind of solution in the nitro-glycerine, making a jelly-like mass (not a powder) which is sensitive to percussion.
- I am also aware that an explosive composition has been made composed of nitro-glycerine, nitro-cellulose, and gunpowder; but in such case the nitrate of potash in the gunpowder is insufficient to oxidize the entire composition, being consumed by the other ingredients of the gunpowder itself—namely, sulphur and charcoal. Moreover, the two latter ingredients produce very deleterious gases on explosion. The composition I have perfected, it will be observed, consists essentially of three ingredients, two of which are explosives and the other an oxidizing agent, which contributes to the total explosive effect of the whole compound in the following manner: Upon explosion any carbon left from the nitro-glycerine and nitro-cellulose in a free state,

from want of sufficient oxygen in those compounds to combine with it and form a gas, is attacked by the oxygen of the oxidizing agent and converted into carbonic-acid gas, which, by the heat produced by the chemical action of such union, is highly expanded and contributes to the total explosive or rending force of the compound. Thus there is nothing inert in my composition; but each ingredient aids in its own way to the general effect.

The advantages of this powder, which is called by me "detonite," are, it retains all the ordinary conveniences of the powder form in other high explosives. It is the strongest blasting-powder of which I have any knowledge. It is the safest strong powder of which I have any knowledge. It can be readily packed in cartridges of any size, and can be safely rammed into the bore-hole, giving greater or less concentration of power according to the degree of compression. The moisture, to which the safety is largely due, is a stable quantity, and is firmly held by capillary attraction in the cartridges, so that the powder is not subject to sudden changes of character from hygrometric or thermometric causes, leading to disasters in its use. So safe is it against blows that a cartridge torn to shreds by a charge from a shot-gun at a few paces will not be exploded by the shock. The gases evolved on the explosion of this powder are less injurious to health.

What I claim, and desire to secure by Letters Patent of the United States, is—

1. A high explosive powder composed of nitro-glycerine, nitro-cellulose, and chlorate (or nitrate) of potash.
2. A high explosive powder composed of nitro-glycerine, nitro-cellulose, and chlorate (or nitrate) of potash, in the proportions substantially as set forth.

WM. R. QUINAN.
